UNITED STATES PATENT OFFICE.

SIDNEY A. REEVE, OF WORCESTER, MASSACHUSETTS, ASSIGNOR TO CHARLES F. BROWN,
TRUSTEE, OF READING, MASSACHUSETTS.

INTERNAL-COMBUSTION ENGINE

No. 899,842.

Specification of Letters Patent. Patented Sept. 29, 1908.

Application filed August 11, 1905. Serial No. 273,710.

To all whom it may concern:

Be it known that I, SIDNEY A. REEVE, a citizen of the United States, residing at Worcester, in the county of Worcester and 5 State of Massachusetts, have invented certain new and useful Improvements in Internal-Combustion Engines, of which the following specification and accompanying drawings illustrate the invention in a form which I 10 now regard as the best out of the various forms in which it may be embodied.

This invention relates to explosive engines operating on the Lenoir cycle modified by initial compression and there are therefore 15 one or more pumps for compressing the charge outside of the combustion-cylinder, and the valve and igniting organs of the combustion-cylinder are such that the compressed charge is drawn into the cylinder 20 during the first part of the stroke, is cut off and exploded, and finally expanded during the remainder of the stroke. Exhaust occurs during the back-stroke and the cycle is then repeated.

25 Formerly it has been proposed to time the ignition with the cut-off, but owing to variations between the piston speed and the rate of flame propagation, differences occurring in the combustibility of the charge, varying de-

gree of compression, and other factors which are constantly changing during the 30 running of the engine, I find that any rigid relation between cut-off and ignition gives inferior results since usually the ignition will 35 either be too early and cause a blow-back or it will be too late and not give the maximum pressure which the particular charge is capable of. I have therefore devised means for effecting the final cut-off of the entering ex-

40 plosive charge by means of the pressure of the explosion. The igniter may therefore have either a fixed or variable point of operation with relation to the piston-stroke but this point will be more or less independent of 45 the point of cut-off since the cut-off is effected by the explosion itself. In carrying out this idea I provide a certain novel form of valve mechanism for the explosion-cylinder and new combinations of igniter and

50 valves, a preferred embodiment of which is hereinafter set forth, and furthermore, since it becomes possible with this new arrangement to secure a wider variation in the composition of the charge and in its rate of mix-

ture and rate of inflammation I provide novel 55 means for varying these factors.

Of the accompanying drawings, Figure 1 represents a side elevation of an explosion motor constructed according to my invention. Fig. 2 represents an end elevation 60 thereof. Fig. 3 represents a top plan view. Fig. 4 represents a top plan view of the explosion-cylinder. Fig. 5 represents a vertical section of the upper end of the latter on the line 5—5 of Fig. 4. Fig. 6 represents a 65 view similar to Fig. 5, showing the cut-off valve open. Fig. 7 represents a horizontal section taken through the inlet and exhaust valves. Figs. 8 and 9 represent views of the 70 igniter in different operative positions. Figs. 10 to 15 inclusive represent detail views of the admission distributing-valve for the air and gas pumps, Fig. 10 being a plan, Fig. 11 a horizontal section, Fig. 12 a rear elevation, Figs. 13 and 14 vertical sections with the 75 valve in two different positions, and Fig. 15 a section on the line 15—15 of Fig. 14.

In the drawings, 1 is the engine-shaft, 2 is the motor-cylinder, 3 is the air-compressor cylinder, and 4 is the gas-compressor cylinder, all of these being double-acting and having the usual pistons (not shown).

5 is the motor-crank, and 6 is the crank for the two compressors set behind the motor-crank by something less than a quadrant 85 so that the pumps are completing the compression of the charge while the motor-piston moves away to form the combustion-space as usual in engines of this type. The compressors may be provided with any of 90 the usual types of valves.

9 is a distributing device controlling the induction of the compressor cylinders so as to provide any degree of mixture of the air and fuel in each compressor short of an explosive mixture. An explosive mixture is highly undesirable owing to the extreme danger of back-firing, but by a certain amount of premixture the speed of inflammation is increased and it is obvious that 100 when this is done by means of the device 9 as I shall hereinafter explain, the increased inflammability, which in an engine with a normally-fixed relation of the ignition and cut-off would require a readjustment of this 105 relation, is in my engine automatically taken care of because cut-off is effected by the explosion.

10 is the air-supply pipe leading into the casing of the distributor 9, and 11 is the gas-supply pipe leading in at an opposite point.

12 is the air-induction pipe of the air-compressor 3, and 13 is a similar induction-pipe for the gas-compressor, these pipes leading out of the distributor-casing above the corresponding pipes 10 and 11. The distributor valve or plug 900 is adjustable through a 10 quadrant and it has two longitudinal surface ports 30 to connect the pipes 10 and 12 and the pipes 11 and 13 so that only air goes to the air-compressor and gas to the gas-compressor, and also four aperture ports 31, for 15 connecting all the pipes with the central chamber of the valve and completely mixing the air and gas for both compressors. By adjusting the valve plug between the two extreme positions represented respectively 20 in Fig. 13 on the one hand and in Figs. 11, 14, and 15 on the other, any desired degree of mixture may be secured so that the air-compressor, for example, will obtain a mixture with too much air to be explosive, and 25 the gas-compressor one with too much gas to be explosive.

14 are the air-compressor discharge-pipes connecting by a trunk-pipe 15 with the air-induction pipes 16 of the motor-cylinder, 30 and 19, 20, 21 are similar pipes for the compressed gas.

17 and 22 represent air and gas induction pipes containing reservoirs 18 and 23 and connecting with the compressed-air and gas 35 lines respectively between the compressors and the motor. Suitable air stop-valves 24, 25, and gas stop-valves 26, 27 are inserted in the piping, and the resulting arrangement is such that the compressors may deliver 40 direct to the motor or may deliver to the motor with reservoirs in lateral branch connection so as to store the compressed fluid and equalize pressure fluctuations, or the motor may receive air and gas direct through 45 the branch pipes 17 and 23 from any suitable source. Furthermore these branch pipes may obviously conduct away to some external destination a part of the compressed air and gas delivered by the compressors.

50 28 and 29 are water-jackets or intercoolers to be used if desired for reducing the temperature of compression of the fluids fed to the motor-cylinder.

Turning now to the automatic valve and 55 igniting arrangements for the motor-cylinder, it will be seen that the compressed air and gas first reach two piston-valves 32, 33 mounted upon a common stem 34 which is actuated in a valve-closing direction by 60 spring 35. The valve arrangements and the igniter arrangements are duplicated at opposite ends of the cylinder so that a description of one end will suffice. 36 is the air-inlet passage for the motor controlled by valve

32, and 37 is the gas-inlet passage controlled 65 by valve 33, these passages becoming concentric at the entrance to the motor-cylinder with a gas-entrance port encircled by an annular air-entrance port, as seen in Figs. 5 and 6, whereby the air and gas become 70 effectively mixed at their entrance; and the two ports are controlled by a single puppet check-valve structure including an annular air-valve 38 and a gas-valve 39 connected therewith by somewhat flexible arms to insure 75 proper seating of both valves. This valve structure has two posts or stems 40, as best seen in Fig. 4, connected above the cylinder-head by a cross-bar 41. Said cross-bar is embraced by the slotted short arm 42 80 of a lever on a shaft 43 and the long arm 44 of this lever has a slot in its end occupied by a pin 46 on a pivoted rock-arm or link 45 which I term a "trip-link", the function thereof being to arrest the closing movement 85 of the valves 38, 39 without shock and lock these valves when seated. When the valves are open as shown in Fig. 6, link 45 is extended parallel to the lever-arm 44, and when the valves are closed the link is 90 brought into a position at right-angles or normal to the lever-arm as indicated by dotted lines in Fig. 5—the link in this latter position locking the lever against any opening movement of the valves 38, 39 due to 95 pressure behind the valves. Fixed to the shaft of the trip-link 45 is a toe 47 adapted to be engaged by a beveled spring-latch 48 on the stem 34 of the piston-valves and thus to swing the link 45 in an unlocking direction 100 when the piston-valves move to the left as viewed in Figs. 5 and 6. When the piston-valves move to the right the latch 48 will be depressed by the toe 47 if the latter is in its vertical position (Fig. 5) and assume a re- 105 engaging position behind said toe.

Piston-valve-stem 34 is drawn out against the tension of spring 35 by the rolling of a wiper-cam 49 which is pivoted to the valve-stem, against a fixed abutment 50, and the 110 cam is oscillated to effect this valve-opening movement by the upward thrust of a rod 56 operated by the eccentric and link motion to be presently described.

52 is the puppet exhaust-valve closed by 115 a spring 53 and operated by a wiper-cam 54 which is pivoted to its stem and acts against a fixed abutment 55. The exhaust-valve is unseated by the downward pull of a rod 56 which oscillates cam 54 and thrusts the exhaust-valve stem inwardly. As it is convenient to actuate the inlet-valves 32, 33 and the exhaust-valve 52 by the same valve motion the respective rods 51 and 56 are connected through suitable rockers and intermediate rods 86, 87 with a rock-shaft 85, but the exhaust-valve might obviously be operated by an independent mechanism worked 120 125

from the cam-shaft and not subject to the same variable control as the inlet-valves, which I shall now describe.

65 and 66 are two eccentrics on the motor-shaft 1 adapted for forward and reverse running respectively and connected by rods 67, 68 with the opposite ends of a Stephenson link 69 which is guided by a rocker-arm 70. In the link are mounted two blocks 81, 82 in 10 guide-ways side by side so as to be capable of sliding past each other, the block 81 being connected with the rock-shaft 85 by means of a rod 83 and rocker 84 so as to operate the admission and exhaust valves, while the 15 block 82 is connected by a rod 88 and rocker-arm 89 with a rock-shaft 90 which operates the igniters as hereinafter described. For shifting the valve-block 81 to vary the amount of opening of the valves and also to 20 time them for reverse running when desired by throwing the block to the opposite end of the link 69, I have shown a rod 101 connected with a bell-crank lever 102 which has a rod 105 connecting with a hand-lever 106, the 25 latter having a suitable latch which co-operates with a fixed toothed segment 107 for maintaining the link-block in a desired adjustment. For shifting the igniter-block 82 there is a rod 112 connected through a bell- 30 crank lever 113 and a rod 115 with a hand-lever 118 which latches in a fixed toothed segment 1070. By this means the ignition may also be timed to occur earlier or later in the working stroke and shifted to one side or 35 the other of dead-center for either forward or reverse running. A rock-shaft 90 connects by a vertical rod 64 with the igniters whose construction is indicated in Figs. 8 and 9.

57 is a fixed electrode within the cylinder, 40 and 58 is a sliding electrode adapted to contact with the fixed electrode and form the spark by separating therefrom, the stem of the movable electrode being connected with a pivoted lever 59 which is moved outwardly 45 by a spring 61 to separate the electrodes. The electrodes are set in contact by the engagement, with a projection on this lever, of a shoulder on a cam-plate 60 oscillated by the rod 64. When thus set the lever 59 is held 50 in position by a latch 62 adapted to be tripped by a detent 63 on the cam-plate 60. For the igniter at the upper end of the cylinder the initial upward movement of cam-plate 60 trips the catch 62 and causes the spark to 55 be formed between the electrodes 57, 58 by the retreat of lever 59, and the continued upward movement of the cam-plate resets the lever. On the downward movement of the cam-plate detent 63 yields to pass the catch 60 62 without actuating the latter. This form of igniter is merely illustrative and any other suitable type can be substituted.

127 is a rod actuated by the hand-lever 106 and connecting with a stop-valve 128 in

the compressed-gas pipe 20, whereby, when 65 the motor is reversed, the gas may be shut off and the motor started on the reverse with compressed air alone from the reservoir 18 and the piping, after which the continued movement of the hand-lever 106 into the full-gear position will re-open the valve 128 and allow the motor to resume the explosive cycle.

200 and 201 indicate the stems of two valves operated by suitable connections 75 from the hand-lever 118 and adapted to be shifted by the same movement which varies the time of ignition. This device represents any standard mechanism for varying the output of the compressors to accord with 80 variations in the load on the motor and the power delivered by the motor.

In the operation of this engine the air and gas compressors 3 and 4 deliver their output to the motor-cylinder 2 under control of the 85 piston admission-valves 32, 33 which are timed with the piston and adjustable in timing by shifting the link-block 81. The piston-valves preferably open at or near dead center and in doing so a latch 48 on the 90 leftwardly-moving valve-stem engages the toe 47 and trips the link 45 so as to unlock the lever 44, 42 which controls the cut-off valves 38, 39, thus enabling the pressure of the air and gas to unseat said valves and admit the 95 charge into the working-cylinder. At any suitable time determined by the adjustment of the igniter-block 82 a spark is formed in the combustible mixture and an explosion takes place. The rise in pressure due to the 100 explosion permits and assists in the closure of the cut-off valves 38, 39 and by the resulting downward movement of lever arm 44 the trip-link 45 is pulled or forced into its vertical locking-position, indicated in Fig. 5. 105 Expansion of the exploded charge takes place during the remainder of the working stroke and on the return stroke the exhaust-valve 52 is opened and the burned gases expelled. The cycle is then repeated. By a preponderant weighting of the longer lever-arm 44 or by an equivalent spring arrangement the 110 cut-off valves 38, 39 may be predisposed to close as soon as the pressures become equalized, and if the explosion is a relatively rapid one, as in most cases, its force will assist the closing movement. It is very important that this closing movement be arrested with as little shock as possible and this I accomplish by the positive mechanical cushioning 115 effect imposed by the link 45 moving into its vertical position of greatest mechanical advantage over the lever and valves, this effect being somewhat like that of a crank and pitman in bringing an engine piston to rest 120 at the end of its stroke, the said link also furnishing an automatic lock which prevents premature opening of the valves 38, 39.

Thus it will be seen that the piston admission-valves 32, 33 after having opened to admit the charge past the check-valves 38, 39, may be closed again either before or after the explosion is complete, and this without either a back-blow or a loss of explosive power, because the final cut-off is effected by the explosion itself and depends upon the relation between the rate of flame propagation and the speed of the piston's retreat. With a slow-burning mixture, ignition would be adjusted to occur relatively early in the working-stroke and might even be instituted at practically dead-center though not completed until a substantial working-charge had entered behind the retreating piston. The admission-distributing-valve 9 controlling the induction of the air and gas compressors gives an opportunity to vary the rate of inflammation by changing the amount of premixture of the air and gas effected in the compressors, and thus enables me in connection with the adjustment of admission and ignition to establish any desired conditions to fit the work performed by the motor, the rate of speed at which it runs, the character of the fuel, etc.

While I have shown hand-regulation for the engine it will of course be understood that various automatic devices known in the art for regulating the engine according to load may be provided and these might take the place of the hand-levers 106 and 118 or operate in conjunction therewith. It will be also apparent to those skilled in the art that the principles of my invention apply to single-acting engines, to non-reversing engines, and to engines using liquid fuel, and also that various well-known devices may be substituted to accomplish the same functions as the link-motions, igniters and other parts described.

The effect of a premature ignition and "blow-back" which the cut-off valves 38, 39 are designed to prevent, would not in the case of the engine illustrated, be more serious than to disturb the proper entrance and further combustion of the charge, unless of course the proportions of air and fuel in either supply pipe were such as to cause the charge to ignite in the supply pipe, which might result from faulty adjustment of air and fuel proportions in the compressor induction. When using liquid fuel, a pump is of course substituted for the gas compressor, and in such cases it is customary to mix the air and fuel completely at some distance anterior to the combustion cylinder. In all such situations the cut-off valve timed by explosion of the charge has a useful office in preventing the effects of a blow-back.

I claim:—

1. An internal-combustion engine comprising a charge-compressor, a combustion-

cylinder adapted to have its charge admitted during the early part of the working-stroke, an igniter, an automatic cut-off valve whose closure is timed by the explosion, a combined cushioning and locking device for said valve adapted to absorb the shock of closing movement of said valve and hold the valve locked in closed position, and means operated by the motor for unlocking said valve.

2. An internal-combustion motor including a combustion-cylinder to which is admitted a charge during the early part of the working-stroke, an automatic valve operated by the explosion for cutting off the charge, and a pivoted arresting-link for said valve forced into a position of greatest mechanical advantage over the valve by the closing movement of the valve.

3. An internal-combustion engine comprising an explosion-motor, a charge-compressor operated thereby, an automatic cut-off valve closed by the explosion, a locking device for holding said valve closed, a charge-admission valve located anterior to said cut-off valve and operated by the motor, and means whereby the opening movement of said admission-valve unlocks the cut-off valve.

4. An internal-combustion engine comprising a motor-cylinder having an inlet-port, an automatic check-valve controlling said port, a lever actuated by the valve, a valve cushioning and locking trip-link operated by the lever, a charge-admission valve anterior to the check-valve and operated by the motor, and means whereby the opening movement of said admission-valve actuates the trip-link to unlock the lever.

5. An internal-combustion engine comprising a motor-cylinder, air and fuel admission passages for said cylinder terminating in concentric entrance-ports, connected admission-valves controlling said passages and operated by the motor, and a single cut-off valve structure adapted to be closed by the explosion and comprising connected concentric air and fuel valves controlling said entrance-ports.

6. An internal-combustion engine comprising a motor-cylinder, a charge-compressor therefor, an admission-valve timed by the motor to admit the charge during the early part of the working stroke, an automatic cut-off valve controlling the charge-admission and closed by the explosion, an igniter, and means for adjusting said igniter to vary the timing thereof with respect to both the working-stroke and the admission-valve action.

7. An internal-combustion engine comprising a motor-cylinder, air and fuel pumping devices therefor, admission mechanism including an automatic cut-off valve closed by the explosion, an igniter having means for

adjusting its timing with respect to the working-stroke, and means controlling the pump-induction for varying the composition and inflammability of the mixture.

- 5 8. An internal-combustion engine comprising an explosion-cylinder adapted to admit, explode, and expand the charge during its working-stroke, air and gas pumps for initially compressing the charge, and a distributing-valve-device controlling the induction of said pumps and having provision for

admitting pure air and fuel to the respective pumps or air-and-fuel mixtures of varying composition.

In testimony whereof I have hereunto set 15 my hand in the presence of two subscribing witnesses, the first day of June 1905.

SIDNEY A. REEVE.
